UNITED STATES PATENT OFFICE.

LOUIS E. WIRTH, OF PITTSBURGH, PENNSYLVANIA, ASSIGNOR TO ALBERT M. HANAUER, OF PITTSBURGH, PENNSYLVANIA.

MECHANISM FOR PICKING AND SEPARATING COTTON FROM FOREIGN MATERIAL.

Application filed July 28, 1924. Serial No. 728,804.

The invention described herein relates to certain improvements in mechanism for picking cotton, of the type or kind in which currents of air are employed for removing the lint from the boll and for effecting a separation of hulls, leaves, pieces thereof, etc., from the lint prior to the latter's being compacted or filled, whereby such foreign matter will become so incorporated with the lint that the fibres must be torn apart to remove the foreign material. The invention is hereinafter more fully described and claimed.

In the accompanying drawings forming a part of this specification, Fig. 1 is a side elevation of a machine embodying the improvements claimed herein; Fig. 2 is a sectional elevation of the elements of the mechanism for segregating the foreign material from the lint; Fig. 3 is a sectional plan view on a plane indicated by the line III—III, Fig. 2, only a portion of the picking cylinder being shown in section; Fig. 4 is a diagrammatic view illustrating connections from the pump to the lint delivery box and Fig. 5 is a diagrammatic view showing connections from the main drive shaft to the pump, separating rolls and wheels of the machine.

In the practice of the invention a pump 1 of any suitable construction is connected by a conduit 2 to the front end of a shell or casing 3 and preferably at a point adjacent the bottom, and the pump is so operated as to maintain a suitable vacuum in the casing. A plurality of nozzles 4 are connected to the top of the casing adjacent the front end thereof and to the outer ends of these nozzles are connected sections of hose 5 provided at their outer ends with nozzles through which, when placed adjacent to a boll, the lint will be drawn by reason of the vacuum in the casing. The streams of air containing the gathers will be directed by the nozzles against the inclined baffle 6 which extends across the casing and has its upper edge forming a tight joint with the top of the casing. Portions of the streams of air carrying the lint will be deflected forwardly across a throat or opening 7 between the lower edge of the baffle 6 and a baffle 8 extending down from the top of the casing in a direction approximately parallel with the baffle 6. Portions of the air carrying the lint will impinge, as indicated by the arrow, on the baffle 6 and be deflected towards the baffle 8 and other portions of the air will flow more or less directly through the throat, as indicated, intersecting the lines of flow towards the throat as indicated by the arrow 6, intersecting the streams of air deflected from the baffle 6. As portions of the air impinging on the baffle 6 may move down along the baffle, and through the throat 7, without being subjected to the separating action due to intersecting streams, as above described, a deflecting ledge 9 is arranged transversely of the baffle 6, whereby any of the streams of air not deflected from the baffle, as described, but flowing down along this baffle, will be deflected upwardly to intersect the streams of the air indicated by the arrow 6. As the gathers of lint are open, i. e., not in any way compacted, and the air will move more rapidly than the gathers, the air will pass through the open gathers and dislodge pieces of leaves, etc., lightly adhering to the fibres composing the gathers.

From the chamber or space between the baffles 6 and 8, the air and lint pass down through the throat 7 onto the grid 10 consisting of spaced but closely adjacent rods underlying the throat 7. This grid extends rearwardly under a pick-up roll and has such a downward inclination that the lint and any foreign material too large to pass between the rods from the grid, will slide down the latter. A baffle 11 is arranged intermediate the grid and the point of connection of the exhaust conduit 2 and extends from the front of the casing in a downward direction nearly to the bottom of the casing, as shown in Fig. 2. By reason of this baffle, the air passing through the throat will flow rearwardly along the grid ensuring the movement of the lint along the grid and under the pick-up roll. As air after passing through the throat could have a tendency to hug the grid, and not exert sufficient force to pull the pieces of leaves, etc. away, from the lint resting on the grid and between the bars forming the grid, perforations are formed through the baffle 11 in line with the direction of flow of air through the throat. This short circuit for a portion of the air will ensure a strong flow of air through the grid and the detachment of small pieces of foreign material from the lint resting on the grid. The pick-up roll 12 is provided on its periphery with teeth so constructed as to engage lint slid-

ing along the grid 10. The roll and grid are arranged in such relation that the teeth will engage the gathers, and the roll is rotated so that its periphery will move in a direction the reverse of that of the lint along the grid. As shown in Fig. 2, the lower ends of the rods forming the grid are supported by a bar 10^a extending across the casing. The ends of this bar rest on adjustable lugs 10^b whereby the distance of the grid from the pick-up roll can be changed. By the rotation of the roll, the lint will be lifted from the grid and during its initial movement from the grid will be subjected to currents of air flowing parallel with the grid whereby foreign material still adherent or mingled with the lint will be segregated from the latter, and will continue along the latter and drop off into the current of air flowing around the end of the baffle 11 and be carried towards the exhaust conduit. In order to prevent the escape of foreign material into the conduit 2, a baffle 13 is so arranged in front of the end 20 of the conduit as to cause an eddying of the air, thus affording opportunity for the foreign material to settle down into a receptacle 14 from which it can be removed through a discharge opening 15 from time to time. 30 The lint is carried along by the roll 12 for a suitable distance and is detached from the teeth of said roll by a rotating brush 16 driven in the reverse direction to that of the roll 12 and the roll and brush and a grid 17 are so arranged that the lint when detached from the roll 12 will drop onto the grid. A baffle 18 is arranged in such relation to the roll that currents of air will flow down between the roll and rotating brush and through the grid 17 and thence under the baffle 11 to the exhaust conduit. There will not be any compacting of the gathers as they are carried around by the roll 12 and swept therefrom by the brush 16; on the contrary, the action of the roll and brush and the current of air passing between 40 will tend to open up the gathers so that when the gathers lodge on the grid the currents of air will flow through the lint and effect a further removal of foreign material from the lint. 50

A further segregation of the foreign material from the lint is effected by a toothed roll 19 similar in construction to the roll 12 and so mounted in the casing relative to the grid 17 which is similar in construction to the grid 10, that the teeth of the roll 19 will pick the lint sliding down the grid and carry it to a point where it will be swept by a rotating brush 21 from the teeth of the roll and deposited in a chamber 20. As before stated, there will be a flow of air down between the roll 12 and brush 16 and through the grid 17. The roll is so located 60 that the current will be tangential to the

upwardly moving portion of the roll 19 and hence will carry foreign material from the lint caught by the teeth of the roll, the periphery of which moves contrary to the direction of flow of the currents of air. 70

It will be observed that any material flow of air from the chamber towards the exhaust conduit 2 is prevented by arranging walls 22 and 22^a in as close proximity as possible to the periphery of the roll, so that although there will be enough leakage past the walls to maintain a vacuum in the chamber 20, there will not be any material current in the chamber, and the lint will drop into pockets 23 in the rotatable drum 23^a. 80 This drum rotates between concave curtain walls 24 to prevent the admission of air into the chamber 20, except such small quantities as may be contained in the pockets. The lint drops from the brush into the pockets 23 and is carried thereby into a chamber 25. In order to remove the lint from the chamber 25, the discharge port 26^a of the exhaust pump is connected to a conduit 26 arranged below and transversely of the pump, and from this conduit at points on opposite sides of the discharge port, extend pipes 27 which are connected to a passage 28 located in front of the box or chamber 25, said-passage having its rear wall perforated to permit of air to enter the box or chamber, as shown in Fig. 4. These jets of air will sweep the lint from the chamber out through a discharge port or opening 29. As only a portion of the air discharged from the pump is required for removing the lint from the box or chamber 25, the ends of the conduit 26 are open and in order to divert air into the pipes 27 leading to the box and chamber, baffles 30 are arranged in the conduit intermediate the open ends of the latter and the points of connection of the pipes 27 therewith. These baffles extend across the conduit distances proportional to the quantities of air required to remove lint from the box or chamber 25. 100

The casing 3 and vacuum pump 1 are so mounted on the chassis of an automobile that the motor of the latter may be utilized for operating the pump and the pick-up rolls and brushes in the casing. As the pump, rolls, and brushes should be operated at high and substantially uniform rates, while the rate of movement of the automobile should be at a rate approximately that of a slow walk, so as to afford the laborers time to move the gathering nozzles from boll to boll, the several parts, i. e., the drive wheels of the automobile, the pump and the pick-up rolls and brushes have independent connections to the shaft of the motor. In the construction of transmitting devices shown in Fig. 4, which have been found suitable, the shaft 31 from the motor is connected through a transmission mechanism of any 110

suitable construction (indicated at 32) to a shaft 33 adapted to be connected by beveled pinions 34 to a shaft 35 arranged transversely of the chassis and having pinions 36 keyed thereon, said pinions intermeshing with an internally toothed ring 37 secured to the rear wheels 38. The shaft 40 of the pump is driven by a chain 41 passing around a sprocket wheel on the motor shaft 31 at a point between the motor and the transmission mechanism as shown in Figs. 1 and 5, so that by adjusting the transmission mechanism the rate of movement of the machine can be varied without varying the rate of operation of the pump. For operating the rolls and brushes in the casing, a gear wheel 42 driven by the motor shaft 31 intermeshes with a pinion on the stub shaft 43 by which a countershaft 44 is driven through a chain 45. This shaft extends rearwardly of the machine and is operatively connected through beveled pinions 46 to a shaft 47 arranged transversely of the chassis. As shown in Figs. 1 and 3, the ends of the several shafts 12^a, 16^a, 19^a and 21^a of the rolls 12 and 19 and brushes 16 and 21 extend beyond the sides of the casing. On these extended ends and the ends of the shaft 47 are secured pulleys for the several belts whereby the rolls and brushes may be driven by the shaft 47. The drum 23^a is driven from the shaft 47 by a belt 48.

I claim herein as my invention:

1. Apparatus for separating foreign material from raw cotton comprising a casing having a receiving chamber, a pick-up roll, a grid arranged transversely of the outlet from said chamber and extending under the pick-up roll, a vacuum pump connected to the casing and a baffle interposed between the grid and the outlet to the vacuum pump, the baffle being so extended that currents of air will flow along the grid and carry lint into position to be caught by the pick-up roll.

2. Apparatus for separating foreign material from raw cotton comprising a casing having a receiving chamber, a pick-up roll, a downwardly inclined grid arranged transversely of the outlet from said chamber and extending under the pick-up roll, a vacuum pump connected to the casing at a point below the grid, and a baffle interposed between the grid and the outlet to the vacuum pump and extending rearwardly beyond the pick-up roll.

3. Apparatus for separating foreign material from raw cotton comprising a casing having a receiving chamber, a pick-up roll arranged in the rear of said chamber, a downwardly inclined grid arranged below said chamber and extending across the outlet from the chamber and under the pick-up roll, a baffle arranged under the grid transversely of the direction of flow of the cur-

rents of air flowing from the receiving chamber and extending rearwardly beyond the pick-up roll, a vacuum pump connected to the casing below said baffle and a second baffle extending upwardly across the outlet to the vacuum pump.

4. Apparatus for separating foreign material from raw cotton comprising a casing having a receiving chamber, a pair of pick-up rolls, one roll being arranged in the rear of the receiving chamber and the second roll in the rear of and below the first roll, revolving brushes for removing lint from the pick-up rolls, a downwardly inclined grid arranged to receive lint from the receiving chamber and direct it to position to be caught by the first pick-up roll and a second grid arranged to receive lint from the first roll and direct it to position to be caught by the second roll, a vacuum pump so connected to the casing that it will cause currents of air to flow through said grid, a downwardly inclined baffle interposed between the first grid and the outlet to the vacuum pump, and means arranged in such relation to the first pick-up roll as to prevent currents of air from flowing forwardly over the top of the first roll.

5. Apparatus for separating foreign material from raw cotton comprising a casing having a receiving chamber, a pair of pick-up rolls, one roll being arranged in the rear of the receiving chamber and the second roll in the rear of the first roll and below the first roll, revolving brushes for removing lint from the pick-up rolls, a downwardly inclined grid extending under the first pick-up roll and arranged to receive lint from the receiving chamber and direct it to position to be caught by the first pick-up roll and a second grid arranged to receive lint from the first pick-up roll and direct it to position to be caught by the second roll, a vacuum pump so connected to the casing as to cause currents of air to flow through said grids, a downwardly inclined baffle interposed between the first grid and the outlet to the vacuum pump, and means arranged in such relation to the first pick-up roll as to prevent currents of air from flowing forwardly over the top of the first roll, a lint receiving chamber enclosing the revolving brush of the second roll, and walls arranged in such relation to the second pick-up roll as to prevent such a flow of air from the lint receiving chamber into the casing.

6. Apparatus for separating foreign material from raw cotton comprising a casing, means arranged in the casing for effecting the separation of foreign material from the lint, a vacuum pump so connected to the casing as to cause currents of air to flow through the casing and in such directions within the casing as to bring the lint into operative relation to the separating means.

in the casing, a lint receiving chamber having an outlet, a second chamber, a rotatable drum having pockets for transferring lint from said receiving chamber into the second chamber, and a pipe extending from the outlet of the pump to said second chamber.

7. Apparatus for separating foreign material from raw cotton comprising a casing, means arranged in the casing for effecting the separation of foreign material from the lint, a vacuum pump so connected to the casing as to cause currents of air to flow in

such directions within the casing as to bring the lint into operative relation to the separating means in the casing, a lint receiving chamber having an outlet, a second chamber, a rotatable drum having pockets for transferring lint from said receiving chamber into the second chamber and means for conducting an air blast to said second chamber. ¹ ²

In testimony whereof, I have hereunto set my hand.

LOUIS E. WIRTH.
